UNITED STATES PATENT OFFICE

GUSTAV ADOLF SCHETTLER, OF LEEDS, ENGLAND, ASSIGNOR TO THE TURNER TANNING MACHINERY COMPANY, OF PORTLAND, MAINE, A CORPORATION OF MAINE

MACHINE FOR OPERATING ON HIDES, SKINS, AND LEATHER

Application filed November 30, 1926, Serial No. 151,772, and in Germany December 18, 1925.

This invention relates to machines for operating upon hides, skins, leather and other similar pieces of work and is illustrated as embodied in a machine of a type which may be readily adapted to such operations as the fleshing, unhairing, putting-out and setting of hides and skins and other pieces of work of considerable size.

At the time of performing unhairing and 10 fleshing operations upon hides and skins the latter are in a condition which makes it very difficult to secure uniformly satisfactory results. Unhairing operations, for instance, are performed upon hides and skins soon 15 after they have been removed from the lime pits wherein they have been subjected to the liming liquors for a period varying between a week and ten days. Immediately before or 20 after unhairing, these same hides and skins are subjected to fleshing operations. In both 25 cases the hides and skins are swollen and slippery and in consequence it is difficult to effect rapid and uniform feeding of the work past the operating tools of the fleshing and 30 unhairing machines. After tanning operations the hides and skins, now in the form 35 of leather, commonly undergo putting-out and setting operations. While the nature of the hide or skin is greatly changed by the 40 tanning operations, so that the slippery characteristic practically disappears, the putting-out and setting tools operate upon the work with so much more pressure than the 45 tools used to treat the hide or skin in its 50 slippery condition that it is necessary for the feeding mechanism to have an unusually good grip on the work to insure proper feeding of the work past the putting-out and setting instrumentalities. Moreover, 55 not only is there difficulty due to slippage of the work in the unhairing and fleshing machines, as above stated, but the operation of the feeding means is not infrequently unsatisfactory because of failure to maintain feeding of the work in a 60 straight line. In other words, certain pieces of work will move laterally to one side or the other of an unhairing or fleshing machine, particularly if, as is commonly the 65 case, the operating tool is a bladed cylinder

with the blades extending helically in opposite directions from points between the ends of the cylinder, with the result that edge portions of the hide or skin may be damaged and imperfectly operated upon. Also, where 55 pieces of work, such as a limed hide or skin, vary considerably in thickness in different portions of each hide or skin, there has always been the possibility of damage to the 60 hide or skin because of failure of the feeding means, and even of clogging of the machine, when a thicker portion comes between the bladed cylinder and the bed roll which 65 co-operate in the fleshing and unhairing operations.

It is an object of this invention to provide an improved machine for operating upon 70 hides, skins, leather and other similar pieces of work, by the use of which the above mentioned difficulties will be overcome, and which 75 will be simple and durable in construction.

To these ends and in accordance with important features of the invention there is provided in the illustrated machine as a part 80 of the feeding means a plurality of helically bladed feeding rolls to provide effective gripping surfaces for feeding pieces of work past a bladed work-operating cylinder, the arrangement being such that the blades of one of the feed rolls are in reversed relation to 85 the blades of the work-operating cylinder so that if the latter should tend to displace the work in a lateral direction during its operation the former would correct this tendency toward lateral displacement of the work, 90 thereby insuring movement of the work in the direction of feed, that is, without lateral movement to one side or the other of the machine. For insuring a rapid and uniform speed in the feeding of the work and obviating all danger of slipping of the feeding means upon the most difficult pieces of work, such as hides and skins fresh from the lime pits, there is preferably provided a pair of feed rolls having helically arranged blades 95 extending in opposite directions from points between the ends of each feed roll and arranged to engage the work successively, both feed rolls co-operating with another roll over 100 which the piece of work passes and against

the surface of which the work is pressed by the bladed feed rolls. As shown, the bladed feed rolls have the helically arranged blades of one roll in reversed relation to the blades of the other roll thereby increasing the effectiveness of the grip on the work and at the same time obviating the possibility of the blades of the second roll impressing themselves upon the surface of the hide or skin at the same places as the blades of the first roll, since if this latter should occur the hide or skin might be injuriously marked at least to the extent of making it very difficult to efface such marks in the operation of finishing the hide or skin to produce a marketable commodity. In the preferred arrangement of the plurality of bladed feed rolls just described, the feed roll nearer the bladed work-operating cylinder has its helically arranged blades in reversed relation to the blades of the cylinder so as to provide means closely adjacent to the cylinder for counteracting the tendency of the latter to displace the work in a lateral direction toward one side of the machine.

These and other features of the invention will be described in detail in the specification and pointed out in the appended claims.

In the drawings,

30 Fig. 1 is a cross sectional view of the work operating parts of a machine illustrating one embodiment of the invention;

Fig. 2 is a view similar to Fig. 1 but showing the parts in work receiving positions;

35 Fig. 3 is a plan view from above intended to disclose the relationship of the helically arranged blades of the feed rolls and of the working cylinder; and

Fig. 4 is an end elevation partly in section showing the present embodiment of the invention.

The illustrated machine, which is designed for performing fleshing operations, is of the type set forth in detail in my copending application now Patent No. 1,683,704, Sept. 11, 1928, to which reference may be had for detailed illustration and description of the construction and operation of parts not fully shown and described herein.

50 In the machine shown there is provided a bed roll 10 for supporting the work while it is being operated upon by a bladed cylinder 12, the bed roll 10 serving not only as a support for the work but as a backing therefor while blades 14 of the cylinder 12 operate successively upon that portion of the piece of work at the time between the bed roll and the cylinder. For feeding a given piece of work such as that shown at 16 past the bladed cylinder 12 there is provided a feeding mechanism comprising a rubber covered roll 18 and two co-operating feed rolls 20 and 22. As shown, the feed rolls 20, 22 co-operate with the roll 18 to provide a substantial lap of the piece of work over the surface of the roll.

18. The arrangement is further such that the feed rolls 18, 20, 22 may be moved away from each other into work receiving position, as indicated in Fig. 2 of the drawings, and as hereinafter described. Simultaneously with this movement the bed roll 10 is moved away from the bladed cylinder 12, by means hereinafter described, so that a piece of work may be thrown over the feed roll 18 and the bed roll 10 preliminarily to an operation of the machine upon the new piece of work thus introduced. 0 75

erally from the line of feed by the blades on that side, since the blades on that side obviously have a greater grip on the work than the blades on the other side of the dividing line. If now, the feed roll 22 which is next to contact with the work should have its helically arranged blades so disposed as to operate as a spreading means this natural tendency to lateral displacement of the work would be increased. Hence, by arranging the blades upon the feed roll 22 in a direction the reverse of the blades on the working cylinder 12, having regard for the fact that the roll 22 and cylinder 12 rotate in opposite directions with respect to each other, this tendency is counteracted and better feeding of the work is secured. Moreover, by reason of the described construction and arrangement of the feed rolls 20 and 22, they serve to grip the work securely in such a way as to provide against slipping of the work during feeding thereof. In this way perfect feeding of the work is secured in spite of the fact that the heavy bladed cylinder 12 is turning in a direction the opposite of that of the movement of the work over the bed roll 10. While for certain classes of work the feed roll 22 may be depended upon in co-operation with the rubber covered roll 18 to feed the work past the bladed work operating cylinder 12, for all heavier classes of work and particularly in fleshing and in setting heavy hides both cylinders 20 and 22 are preferably used in co-operation with the rubber covered roll.

The means for moving the bed roll 10 and the feed rolls 20 and 22 between work receiving and work operating positions, referred to earlier in this specification, will now be described. Upon inspection of Fig. 4 of the drawings it will be observed that the bed roll 10 and the feed roll 18 are mounted upon a carriage 30 slideable upon a supporting member 32 carried by frame 34 of the machine. For reciprocating the carriage 30 there is provided a toggle mechanism comprising a lever 36 pivoted at 38 to the support 32, the lever 36 being connected to the carriage 30 by a link 40 pivoted to the lever 36 at 42 and to the carriage 30 at 44. For operating this toggle mechanism there is provided a crank 46 upon a shaft 48, a connecting rod 50 extending between the crank 46 and the lever 36 and being connected to the lever by a pivot member 52. It will be clear that upon rotation of the shaft 48 the toggle will be alternately straightened and broken and that during the straightening of the toggle the carriage 30 will be moved to position the bed roll 10 in cooperative relation with respect to the bladed cylinder 12. At the same time the feed roll 18 will be moved into cooperative relation with respect to the feed roll 22 upon a shaft 54 carried by arms 56 extending from the supporting mem-

ber 32. Connected to the lever 36 at a point 58 in the end of an extension of the lever is a link 60 which is yieldingly connected to a swing arm 62, a companion swing arm, not shown, and the swing arm 62 being mounted to swing upon the shaft 54. Mounted upon the swing arms 62 is a shaft 64 which carries the feed roll 20. It follows that, when the carriage 30 is moved toward operative position for the bed roll 10, the feed roll 20 is swung downwardly and over the feed roll 18 into the position indicated in Fig. 1, the feed roll 20 being moved yieldingly to its operative position by reason of a spring 70 upon the end of the link 60. At the end of the described movements of the carriage 30 and the swing arms 62 the bed roll 10 and the feed rolls 18, 20 and 22 occupy the position shown in Fig. 1. Upon breaking of the toggle comprising the toggle members 36 and 40 the carriage is moved in the reverse direction and the swing arms 62 are moved upwardly, thereby moving the parts to work receiving positions, indicated in Fig. 2 of the drawings. In this position of the parts the hide or skin 16 may be readily thrown over the feed roll 18 and over the bed roll 10 and maintained in that position while the toggle mechanism is operated to move the parts to work operating position, as already described. Power means is provided for driving the bladed cylinder 12 continuously in the direction indicated by the arrow in Fig. 1 and connections are provided for driving the feed rolls 18, 20 and 22 in feeding direction, as indicated by the arrows in the same figure. These driving means are not disclosed in the drawing for the reason that they may be, and preferably are, constructed and arranged in a manner similar to the driving parts for the corresponding elements in the machine of the copending application, now Patent No. 1,683,704 September 11, 1928, already referred to.

Having thus described my invention, what I claim as new and desire to secure by Letters Patent of the United States is:

1. In a machine for operating upon hides, skins, leather and other similar pieces of work, a feeding mechanism comprising a rubber covered feed roll, a feed roll for co-operation therewith having helically arranged blades extending in opposite directions from points between the ends of the feed roll, and a feed roll having helically arranged blades in reversed relation to the blades of the first bladed-roll.

2. In a machine for operating upon hides, skins, leather and other similar pieces of work, a feeding mechanism comprising a feed roll, and a pair of feed rolls each arranged to co-operate directly with the first-mentioned feed roll and each having helically arranged blades extending in opposite directions from

points between the ends of the respective feed rolls.

3. In a machine for operating upon hides, skins, leather and other similar pieces of work, a feeding mechanism comprising a feed roll, and a pair of feed rolls for co-operation with the first-mentioned roll, and each of the pair of feed rolls having helically arranged blades extending in opposite directions from points between the ends of the respective feed rolls, the blades of one roll being in reversed relation to the blades of the other roll so that during the feeding operation the blades of one roll operate to spread the work and the other to contract it in the same direction.

4. In a machine for operating upon hides, skins, leather and other similar pieces of work, a bladed cylinder for operating on the work having helically arranged blades extending in opposite directions from points between the ends of the cylinder, a bed roll for supporting the work against the thrust of the blades, and means for feeding the work past the cylinder comprising two feed rolls having helically arranged blades extended in opposite directions from points between the ends of each feed roll, the blades of one feed roll being in reversed relation to the blades of the working cylinder so that these blades tend to counteract sidewise movement of the work by the blades of the cylinder.

5. In a machine for operating upon hides, skins, leather and other similar pieces of work, a bladed cylinder for operating on the work having helically arranged blades extending in opposite directions from points between the ends of the cylinder, a bed roll for supporting the work against the thrust of the blades, and a plurality of feed rolls for feeding the work past the cylinder, one of the feed rolls having a rubber covered surface and another feed roll having helically arranged blades extended in opposite directions from points between the ends of the feed roll, the blades of said feed roll being in reversed relation to the blades of the working cylinder so that these blades tend to counteract sidewise movement of the work by the blades of the cylinder.

6. In a machine for operating upon hides, skins, leather and other similar pieces of work, a helically bladed cylinder for operating on the work, a member for supporting the work against the cylinder, and a plurality of feed rolls for feeding the work past the cylinder, one of the feed rolls having helical blades disposed similarly to those of the bladed cylinder and another of the feed rolls having helical blades disposed reversely to the blades of the first-mentioned bladed feed roll.

7. In a machine for operating upon hides, skins, leather and other similar pieces of work, a bladed cylinder for operating on the work having helically arranged blades extending in opposite directions from points

between the ends of the cylinder, a bed roll for supporting the work against the thrust of the blades, and a plurality of feed rolls for feeding the work past the cylinder, one of the feed rolls having helically arranged blades disposed similarly to those of the bladed cylinder and another feed roll having helically arranged blades disposed reversely to the blades of the other feed roll.

8. In a machine for operating upon hides, skins, leather and similar pieces of work, a helically bladed cylinder for operating on the work, a member for supporting the work against the cylinder, and means comprising a plurality of helically bladed feed rolls for feeding the work past the cylinder, one of the feed rolls having blades disposed reversely to the blades of the cylinder.

In testimony whereof I have signed my name to this specification.

GUSTAV ADOLF SCHETTLER.
